TRACK CONSTRUCTION

Lester T. Burwell, Maplewood, N. J.

Application March 11, 1938, Serial No. 195,243

1 Claim. (Cl. 238—349)

My invention relates to track construction and has particular reference to the holding of rail against longitudinal creeping or expansion (which term also includes contraction) due to 5 temperature changes, and the provision of a suitable tieplate and fastenings.

My present invention has particular reference to open track above surface, laid on tieplates fastened to ties which are embedded in ballast, preferably cinder or stone, the rail being subject to a wide range of temperature from mid-summer sun to the cold of winter. While holding the rail against expansion and permitting the rail to be laid without expansion 10 gaps, my invention also contemplates holding a rail against creeping caused by traffic, by braking, or by other forces and conditions.

An object of my invention is to provide a 20 comparatively low cost improved track construction which is safe. A further object of this invention is to provide means and method of holding a rail without restricting the wave motion but which limits the upward movement of the rail whether due to wave motion or not.

In general I prefer to provide a rail seat on 25 the tieplate, preferably crowned or cambered to provide line contact only between the rail and the tieplate. I prefer to provide shoulders on both sides of the rail seat or equivalent bulwarks 30 against lateral movement of the rail. I prefer to permit the rail to have free and unrestrained vertical motion between the bulwarks but definitely to limit the extent of that free motion to a safe amount so that there can be no danger 35 of the rail jumping the shoulders or escaping if the rail fasteners should break, become dislodged or be destroyed. In such construction, my invention contemplates a rail fastener firmly gripping the base flange of the rail top and bottom, 40 that part of the rail fastener which grips the bottom of the rail flange to be confined in an opening in the tieplate abutting both sides of said opening at a point below the rail so that the restraining force of the tieplate on the fastener acts in or close to the plane of the gripping 45 force of the fastener on the rail, to avoid "pivoting" of the rail fastener with consequently play and loss of grip.

I prefer that the construction of the opening 50 in the tieplate be such that the fastener may be driven into position with a spike maul or the like and thereafter a rail spike or other tieplate fastening be driven into a prepared outer portion of the tieplate opening or elsewhere, where it 55 performs its main functions of holding down the tieplate and of overlying the rail or rail fastener, preferably both, but the overlying portion spaced from the part it overlies so as to limit but not prohibit upward motion of the rail. The tieplate fastening may but does not necessarily 60

form the sole backing for the rail fastener. Where it does form such sole backing it preferably acts as a block between the edge of the tieplate opening and the back of the rail fastener, on which the rail fastener slides up and down 5 and in such case the block or spike may be of hardened spring metal as is the rail fastener itself.

I prefer that the dimensions of the rail fastener shall not affect the dimensions of the tieplate 10 holding means, or vice versa, and to that end that the tieplate opening be larger or smaller, as is required, at the outer end so that the tieplate fastener shall fit into the tieplate opening 15 and thus the tieplate be prevented from moving 15 on the tie.

Lastly, my invention contemplates a balanced 20 rail fastening for each tie to prevent either splitting, rolling or "slewing" the tie, by placing the rail fasteners diagonally across the rail from each other, one on one side of the center line and the other on the opposite side of the center line or line of contact between rail and tieplate. Preferably, the center line of rail, tieplate and tie are undisturbed by this construction. I may 25 similarly stagger the tieplate fastenings also, on tangent track.

With the foregoing and other objects in view, as will be apparent as the description proceeds, 30 my invention resides in the combination and arrangement of parts and in the details of construction described in this specification and particularly pointed out in the appended claim. I intend no limitation other than those of the 35 claim when fairly interpreted in the light of the full disclosure and the present state of the art, it being understood that changes may be made within the scope of what is claimed without departing from the spirit of the invention.

In the drawing, illustrative of a preferred 40 and other modifications of my invention, Fig. 1 is a fragmentary cross sectional elevation of a rail, tieplate, rail fastener and tieplate fastener disposed according to my invention; Fig. 2 is a fragmentary sectional plan view at the surface 45 of the tieplate in Fig. 1; Fig. 3 is a sketch of the tieplate fastener of Fig. 1; Figs. 4 and 5 are views similar to Figs. 1 and 2, of a modification 50 of my invention; Figs. 6 and 7 are similar views of another modification; Fig. 8 is a sketch of the modified rail fastening of Figs. 6 and 7; Fig. 9 is a sketch of still another modified form of my invention; Fig. 10 is a fragmentary section on the line 10 of Fig. 9; Fig. 11 is a plan view of the arrangement of a tieplate and fastenings 55 according to the device of Fig. 1.

Similar reference characters relate to corresponding parts throughout the several views.

In the drawing is illustrated a rail base 1 which rests on a tieplate 2 which is supported on a tie, 60

as 3 (Fig. 11). The tieplate is preferably cambered or crowned, as at 4, and preferably is double shouldered 5, 5, (Fig. 11) and provided with a spike hole on each side 6, 6, adjacent the rail, in addition to the opening provided for the rail fastener.

To hold the tieplate to the tie, various forms of "spike" fastenings may be used, the particular form of the spike not being my invention but 10 designated herein as 7, 7A, 7B, the spike 7 (Fig. 6) being an ordinary rail spike, spike 7A being a form of resilient wedge spring spike, 7B illustrative of a full throated cut spike of well known construction. Various spike combinations may 15 be used, as suggested in the arrangement of Fig. 9, described below.

Besides the usual rail spike holes diagonally disposed, the tieplate 2 is provided on each side of the rail seat with an opening 8 under the 20 rail and extending outwardly beyond the rail edge a greater distance than the spike hole, the outer end preferably widened in the arrangement of Figs. 1 and 2, but narrowed in the arrangement of Figs. 4 and 5, of the same size (Fig. 25 9) or divided to form a U-shape (Figs. 6 and 7).

A rail fastener of resilient material 9, preferably U-shaped, which may be relatively elongated 9A (Fig. 4) or slotted 9B (Figs. 6 and 8), is provided to be driven on the edge portion of 30 the rail base 1 and to fit into a slot 8 so as to abut both side walls thereof at points below the rail base, the gripping force of said fastener being sufficient to restrain longitudinal movement or 35 expansion of the rail. This fastener is adapted to be driven by a spike maul or the like and may be held from backing off or release, by abutting the edges 10 (Fig. 5) of the tieplate opening. It is apparent that in this instance, the opening 8 extends out from the rail edge a 40 distance less than the length of the lower portion of the rail fastener 9A.

Preferably the opening 8 extends a distance greater than the length of the lower portion 45 of the rail fastener 9 so that the fastener may be dropped into the opening and driven into place without lifting the rail. In such instances the outer end of the opening may widen abruptly to provide abutment shoulders 11 (Fig. 2) for the tieplate fastenings, in this instance the spring 50 spike 7A, against the hardened surface of which the rail fastener 9 may slide up and down, limited by the overhanging arm 12 (Fig. 1) which extends over the rail but is spaced therefrom. A portion 13 on the other leg of the spring spike 7A 55 serves to limit the amount it can be driven, as does the full throat 14 of the spike 7B (Fig. 4). In the latter instance the outer portion of the opening 8 is narrowed and fits the spike 7B so that the tieplate is held from movement on the 60 tie. It is essential for the tieplate to be held when on a wooden tie not only to prevent movement of the rail; but also to prolong the life of the tie.

If the rail fastener 9B is slotted through the bend of the U, a U-shaped opening may be provided at the outer end of the opening 8 and the spike 7 may be against the rail edge and abut the tieplate portion 16 (Fig. 7), the spike head overlying both the fastener 9B and the rail 1, the rail fastening 9B also held from backing off by 70 the spike 7 and, in turn, furnishing a filler portion on each side of the spike to prevent tieplate movement on the tie.

In some instances I may prefer to dispose the several parts as indicated in Fig. 9, the fastener 9 being of spike width and backed up by a blocking spike 7 in the outer part of the opening 8. Alongside the rail I also provide in an ordinary rail spike hole 6, a spring spike 7A, for example, generally of spike dimensions, overlying the rail to limit upward motion (Fig. 10) and serving to hold the tieplate 2 to the tie by the spring wedging effect in the spike hole 6 and an anchor below the 10 tieplate in the tie.

Preferably, as in Fig. 11, rail spike holes 6 are provided, one on each side of the rail seat, for emergency, and the rail fastener and tieplate fastening on one side of the rail is in a different opening which extends under the rail seat and out from the rail edge a greater distance than the ordinary spike hole 6. These fastenings on one side of the rail are preferably diagonally disposed from similar fastenings on the other side of the rail and are on the opposite side of the contact line, thus providing a balanced rail fastening with free movement up and down of the fastened rail portions at these points of substantially greatest rail flexure over the tieplate, one fastening on each side of the rail and one fastening on the approach side of the center line of contact and another on the departing side and the spikes are not in the same grain of the tie or along the rolling axis. The holding forces on the rail act on each side below the base of the rail and are equalized. My invention, as thus set forth, has particular efficacy in holding long welded rails or successive rails not welded but with ends butted together without expansion gaps.

What I claim is:

In a railroad track construction, in combination, a rail so laid as to be effected by temperature changes and free from any embedding material and a support therefor including a tie anchored in ballast and a tieplate between said rail and said tie provided with an opening therein under the rail and extending outwardly beyond the edge of the rail base and changing abruptly to greater width at the outer end thereby providing abutment edges for a tieplate fastener, a rail fastener comprising a resilient clamping member gripping the rail base top and bottom and provided with a lower portion thereof clamped against the under side of the rail base and positioned in said tieplate opening in abutting relation to the side walls thereof below the rail of such character that the rail is held from longitudinal creeping or expansion due to temperature changes and is permitted free upward movement during wave motion, and other means to limit the extent of such free upward movement comprising a tieplate fastener positioned in the wide outer end portion of said tieplate opening resiliently wedged between the outer wall thereof and said abutment edges and anchored in said tie and thereby serving to hold said tieplate and in frictional engagement with said rail fastener to prevent release of the latter, said tieplate fastener presenting a hardened surface to said rail fastener and provided with a portion extending over said fastener of such character that the upward motion thereof is limited and thereby limits the upward movement of said rail during wave motion.

LESTER T. BURWELL.
